UNITED STATES PATENT OFFICE.

JAMES HARRISON, OF BROOKLYN, NEW YORK.

DENOMINATING MACHINE.

Application filed February 26, 1924. Serial No. 695,239.

The invention relates to improvements in machines for dividing sums of money and performing certain counting functions and which may be designated briefly as a denominating machine and somewhat similar to a machine disclosed in a copending application filed March 20th, 1923, Serial Number 626,320.

The invention provides a denominating machine which divides sums of money into bills and coins of convenient denomination in use in any particular country, conveniently the least number of bills and coins to make up the sum divided. It also provides a machine which counts the various units of each denomination in a plurality of sums which have been divided. The invention is especially intended to aid paymasters and others in ascertaining the total monies of different denomination which it is necessary to obtain to pay a number of individuals separate sums of money, without making change, and with the handling of the least number of bills and coins; it may be thereafter used to indicate the number and denomination to be selected in making payment of the various sums to be paid out.

Another object of the invention is to provide a denominating machine which can be manufactured and sold for a relatively small price, which is simple, has comparatively few parts and does not require a skilled mechanic to repair.

An embodiment of the invention is illustrated in the accompanying drawings, in which—

Figure 1 is a top plan view of the machine with parts broken away for the sake of clearness.

Figure 2 is a side elevational view of the machine.

Figure 3 is a detail view of a part of the operating mechanism.

Figure 4 is a detail perspective view of a part of the operating mechanism showing a key and related mechanism for denominating or dividing the specific sum of 40 cents, and

Figure 5 is a diagrammatic view of all of the keys and operating levers of the machine.

Referring to the drawings in detail, 1

designates the casing, 2 the dividing or denominating mechanism and 3 the counting mechanism.

The denominating mechanism is here shown and described as adapted for denominating money in current use in the United States of America. It is apparent however that the same operating principle may be utilized for the purpose of denominating currency used in foreign countries. The denominating mechanism comprises a plurality of keys 5, which are divided into two series, one designated by the numeral 6 for coins (silver and pennies) to wit, halves, quarters, dimes, nickels and pennies, and a second series 7 for bills (paper monies) in the usual denominations of bills in use, as for example, one, two, five, ten, twenty, fifty and one hundred dollar bills. The coin series 6 of the keys is provided in multiples of 1 up to and including 9 for pennies and 10 up to 90 for silver or 26 keys in all. The bill series 7 comprises a digit column in multiple of 1 up to 9 and a tens column in multiples of 10 up to and including 50 and a 100 key for the hundred, or 15 keys in all.

Numerical 8 designates a plurality of levers which are selectively operated by the keys 5, as will be more fully explained; these levers being arranged in two series 9 and 10 of nine each, corresponding to the series 6 and 7 of the keys 5. There is a lever 8 for each denomination of money in use—that is, there are levers 11, 12, 13, 14, 15, 16, 17, 18 and 19 for the 50¢, 25¢, 10¢, 5¢, 3¢, 2¢, 1¢ and an extra lever for the 10¢ coin, and levers 20, 21, 22, 23, 24, 25, 26, 27, and 28 for the \$100, \$50, \$10, \$5, \$2, \$1 and extra levers for the \$10 and \$1 bills. In the detail views Figures 4 and 5, the denomination of the lever has been placed adjacent the same in a circle.

Each key 5 has an adjustable means associated therewith for selectively operating the appropriate lever or levers 8 when it is operated. For example, the key for 40¢ in the silver and penny series 6 when operated would operate the individual levers 12 (25¢), 13 (10¢) and 15 (5¢) and no others. These means, as shown in Figures 3 and 4 consist of rods or arms 30 crossing the levers 8 which are pivotally mounted at one end on rods 31 and 32 located on opposite sides of

the machine. The keys 5 are pivotally connected to the other ends of the rods and the rods have headed adjusting screws 33 mounted thereon and the heads of the screws are 5 arranged to engage the particular lever or levers beneath the key so that when the key is pressed, only those levers 8 will be operated which contact with the screws 33. Thus under the 40¢ key (see Figure 4) the 10 levers 12, 13 and 15 will be operated. A suitable lock nut 34 is provided on the adjusting screw 33 for securely locking the screw in its adjusted position on the rod 30. These adjusting screws are provided to 15 regulate the throw of the various keys and levers so as to effectively actuate the counting mechanism.

The key rods 30 are normally held in their upper position by means of springs 20 30' which are secured at one end to a part of the machine frame and have their other end engaging the under surface of the key rods as shown in Figure 4. A bar 32' limits the upward movement of the key rods and 25 downwardly projecting guide fingers 33' are provided on the bar 32' between which the key rods 30 travel.

The levers 8 are suitably pivoted at one end, on a rod 35 supported on uprights 36 30 and are connected at their other end to a return spring 37, one end of which is secured to the lever and the other end to a rod 38 mounted in the frame of the machine.

Each lever 8 has a counting device 3 as- 35 sociated therewith. This counting device may be of any suitable character that has units, tens and hundreds number wheels to indicate the total amounts of the bills and coins of different denominations required 40 and the counters are visible through openings in the top of casing 1. Each counter is provided with an operating rod 40 secured at one end to the lever 8 and on the other end of the rod is pivotally secured a 45 spring pressed pawl 41, for engaging the ratchet 42 and actuating the counter when the lever 8 is returned to its upper position by the spring 37. To prevent the backward movement of the counters the usual spring 50 pressed pawls 43 are provided and these are mounted on the upper ends of rods 44 secured to cross bars 45 mounted in the frame of the machine. As the counters are of the usual construction it is not thought necessary 55 to describe them further in detail.

Now for example, if a key is depressed its corresponding lever or levers will be thrown downwardly. This will cause the operating rod 40 and its pawl 41 to travel 60 downwardly and the pawl will escape around the ratchet 42 so that the counter will not be actuated. Upon the return of the lever, the pawl will engage the ratchet 42 and the counter will be advanced one step

bringing the advanced number into view on 65 the counting device.

In order to reset the counting devices to zero or initial position, a reset key is employed by securing it to the squared ends of the shafts 45 and 46 (see Fig. 3) on 70 which the counters are mounted, and turning the shafts counter clockwise until all of the counters register zero.

Examples of operation of the machine in denominating specific sums and counting 75 the denominations of money in such sums will be described.

\$13.43: To denominate this sum, the \$10. key in the tens column and the \$3. in the digits column of series 7, the 40¢ key and 80 the 3¢ key in the series 6 are pressed. The \$10. key operates (through rod 30 thereon) lever 24 (\$10.); the \$3. key operates levers 26 (\$2.) and lever 27 (\$1.); the 40¢ key operates levers 12 (25¢) 13, (10¢) and 15, 85 (5¢) and the 3¢ key operates lever 17 (3¢). Each lever operates its corresponding counting mechanism advancing the same one step and registering thereon 1—\$10., 1—\$2., and 1—\$1., 1—25¢, 1—10¢, 1—5¢ and 3—1¢. 90

\$29.49: To denominate this sum, the \$20. key in the tens column and the \$9. key in the digits column of the series 7 is operated; also the 40¢ key and the 9¢ key of the series 6 is operated. The \$20. key operates lever 95 23 (\$20.); the key \$9. key operates levers 25 (\$5.), 26 (\$2.) 27 (\$1.) and 28 (\$1.). The 40¢ key operates levers 12 (25¢), 13 (10¢), 15 (5¢), and the 9¢ key operates levers 15 (5¢), and 16 (4¢). Each of these 100 levers operates its corresponding counting mechanism advancing the same one step and registering thereon 1—\$20., 1—\$5., 1—\$2. and 2—\$1. and 1—25¢, 1—10¢, 1—5¢, 1—5¢ and 1—4¢.

It is obvious that those skilled in the art may vary the details of construction and arrangement of parts without departing from the spirit of my invention, and, therefore, I do not wish to be limited to such features, except as may be required by the 105 claims.

What I claim is—

1. A denominating machine, comprising numbered keys, a plurality of pivoted levers corresponding to denominations of money, counting mechanism operated by the movement of said levers, and means operated by said keys for selectively operating the said levers, according to the denominations of 115 money making a sum corresponding to the number of the key operated, said means comprising bars above and crossing said levers and pivoted at the sides of the machine, and said bars having adjustable and detachable projections for engaging said levers. 120

2. A denominating machine comprising 125

numbered keys, a plurality of pivoted levers corresponding to denominations of money, counting mechanism operated by the movement of said levers and means operated by 5 said keys for selectively operating the said levers according to the denominations of money making a sum corresponding to the number of the key operated, said selective means comprising adjustable projections re- 10 movably supported from said keys for engaging said levers.

3. A denominating machine comprising a plurality of pivoted levers corresponding to denominations of money, counting mechanism 15 connected to and operated by the movements of said levers, spring pressed key bars above and crossing said levers and pivoted at the sides of the machine, numbered keys pivotally connected to said bars and means 20 operated by said keys for selectively operating the said levers, according to the denominations of money making a sum corresponding to the number of the key operated, said

selective means comprising adjustable and detachable projections from said keys for 25 engaging said levers.

4. A denominating machine comprising keys, a registering mechanism, selector mechanism controlled by said keys for operating said registering mechanism including 30 two overlapping groups of pivoted levers disposed at right angles to each other.

5. A denominating machine comprising a machine casing, numeral keys, pivoted levers, counting mechanism operated by the 35 movement of said levers, and means operated by said keys for selectively operating the said levers according to the denominations of money making a sum corresponding to the number of the keys operated, said 40 means including bars pivoted at the walls of the machine casing.

In testimony whereof, I have signed my name to this specification this 23rd day of February 1924.

JAS. HARRISON.
